UNITED STATES PATENT OFFICE.

ALBERT D. GROVER, OF NEW YORK, N. Y.

MULTIPLE-WRENCH TOOL.

1,321,625.

Specification of Letters Patent. Patented Nov. 11, 1919.

Application filed August 16, 1917. Serial No. 186,460.

To all whom it may concern:

Be it known that I, ALBERT D. GROVER, a citizen of the United States, and resident of New York, county and State of New 5 York, have invented certain new and useful Improvements in Multiple-Wrench Tools, of which the following is a specification.

The object of my invention is to provide a new and improved wrench which is small 10 and compact and is readily adjustable for nuts of different sizes. The instrument consists of but few parts and is so small that it can be carried about in the pocket.

The objects and advantages of my invention will become apparent from a detailed description of the accompanying drawings, which show a preferred embodiment of my invention.

In these drawings,

20 Figure 1 shows my new and improved wrench tool in side elevation, the wrench member being locked in operative position;

Fig. 2 is a longitudinal cross-section on line 2—2 of Fig. 1;

25 Fig. 3 is a view similar to Fig. 1 with one of the handle plates or members removed for the sake of clearness, the parts being shown in such position that the tool may be used as a screw-driver; and

30 Fig. 4 is a transverse cross-section on line 4—4 of Fig. 1, looking downward.

On suitable form of handle 1 is pivoted a rotary wrench member 2 by means of a stud 3. In the present instance, I have 35 shown the handle 1 as consisting of a pair of plates secured together and properly spaced by the shoulder rivets or studs 3 and 4. If desired, however, the handle need but consist of a single member.

40 The wrench member 2 is provided with a series of jaws 5, 6, 7 and 8. The number and different sizes of these jaws may vary to suit the particular purpose for which the tool is intended. In the particular embodiment illustrated in the drawings, the wrench member 2 is intended to be used for adjusting the nuts of banjos of different sizes.

Between the handle members 1, is mounted 50 a slide 9, best shown in Fig. 3. This slide is supported and guided by the studs 4 and 10. The stud 10 is preferably not riveted to the handle, so as to allow the same to spread apart slightly at the center, for reasons to be presently explained. The slide 9 is provided with slots 11 and 12 which

limit the in and out movements of the slide. The slide 9 is locked in either of its positions by frictional projections 13 formed in the handle 1 and adapted to enter the 60 opening or recess 14 in the slide 9 when the latter is in wrench-locking position, as shown in Figs. 1 and 2. Although I have shown a pair of frictional projections 13, but one might be found sufficient in some 65 forms of my instrument. At its lower end, the slide 9 is provided with a pair of lateral locking extensions 15, so constructed and arranged as to engage the shoulders 16 of the rotary wrench member 2, whereby 70 the latter is securely locked in operative position. This is clearly shown in Fig. 1.

In the present instance, the shoulders 16 are formed by cutting notches in the periphery of the wrench member 2, but it is 75 obvious that they may be formed in any other suitable way.

The slide 9 is also provided at its lower end with a central extension 17 adapted to engage one of the shoulders 16 of the rotary 80 wrench member 2, when the slide 9 is to be used in withdrawn position, as indicated in Fig. 3. The outer end 18 of the slide 9 is in the form of a suitable tool. Obviously, in the broad aspect of my invention, the particular form of function of the outer head 85 18, which may be referred to as an operative head, is immaterial. For the sake of illustration I have shown the head 18 as a screw-driver. When the slide 9 is in inner 90 or wrench-locking position, as shown in Figs. 1 and 2, the central extension 17 rests in one of the jaws of the wrench member, and the head 18 lies within the handle 1. This not only keeps the screw-driver head 18 out of 95 the way when the instrument is used as a wrench, but it also makes it easier and safer for a person to carry the tool in his pocket.

When it is desired to use the head 18, in 100 this instance a screw-driver, it is only necessary to grasp the slide by the lateral projections 19 and pull it out until the central extension 17 is clear of the wrench member 2, whereupon the latter may be rotated until 105 one of the notches 16 comes beneath the extension 17. In this position of the slide 9, the head 18 projects beyond the handle and the instrument may be used as a screw-driver, or whatever tool the head 18 may 110 represent. Any thrust or pressure brought to bear upon the slide 9 when used as a

screw-driver or other tool, is taken up by the wrench member 2, as will be clear from Fig. 3. In other words, when the head 18 is in operative position, the wrench member 5 2 constitutes a support or bearing for the slide 9 to prevent longitudinal inward movement of the slide and head. The slide 9 is further steadied in its withdrawn position by the pressure of the frictional projections 13 against the sides of the slide. As previously stated, the stud 10 is not riveted to the handles 1, but is merely used as a guide and allows the handles to serve as springs when the slide 9 is moved from one 15 position to the other.

As may be seen from Fig. 3, although the wrench jaws 5, 6, 7 and 8 are of different widths to fit onto nuts of different sizes, they are of substantially the same depth. This 20 feature of construction enables the extension 17 of the slide 9 to project fully into the jaws, thus insuring full and firm contact between the lateral locking extensions 15 and the shoulders 16 of the wrench member 2.

If desired, the slide 9 may be provided with one or more cutting edges 20 which are exposed for use by the cut-away portions 21 of the handle, as best shown in Fig. 1. 30 These knife or cutting edges may serve various purposes—such as, insulation scrapers, banjo string cutters, wire cutters, etc.

It will be seen from the foregoing, that I have provided an exceedingly simple, compact and efficient tool which embodies several useful instruments in one. The wrench member 2 is readily adjustable to bring any of the desired jaws into operative position, and is securely locked in that position. To 40 use the instrument as a screw-driver, all that a person has to do is to pull out the slide 9 by means of the finger pieces 19 and turn the wrench wheel 2 into such position that one of the notches 16 will come into 45 alignment with the central extension 17 of the slide 9.

By providing the cutting edges 20 near the lateral finger pieces 19, the latter act as a guard or protection against a person accidentally cutting himself on the knife edges 20. When the slide is in extended position, as shown in Fig. 3, the knife edges 20 are in concealed position. Although I have herein shown two knife edges, it is obvious that but one is necessary.

For delicate work, such as adjusting nuts on banjos and the like, the tool of my invention may be made very small and flat, so that it may be carried in the pocket, the 60 same as an ordinary pocket knife. For heavier work, the parts will, of course, be made stronger and correspondingly larger.

Although I have herein illustrated and described a specific form of tool, I will have 65 it understood that I do not intend to be lim-

ited to the precise details of construction set forth.

Having thus described my invention what I claim as new and desire to secure by Letters Patent of the United States, is:

1. In a tool of the class described, a handle, a wrench member pivoted on said handle, said member being provided with a plurality of wrench jaws and rotatable to bring the desired jaw into operative position, a slide adjustably mounted on said handle, and coöperating means on said slide and said wrench member whereby said slide grips said member at points on opposite sides of one of said jaws for securely locking said member in any one of its operative positions. 70

2. In a tool of the class described, a handle, a wrench member pivoted on said handle, said member being provided with a plurality of wrench jaws and with shoulders arranged between said jaws, said member being rotatable to bring the desired jaw into operative position, a slide adjustably mounted on said handle, and a pair of lateral extensions on said slide for engaging a corresponding pair of said shoulders, whereby said wrench member is securely locked in operative position. 80

3. In a tool of the class described, a handle, a wrench member pivoted on said handle, said member being provided with a plurality of wrench jaws and rotatable to bring the desired jaw into operative position, a slide adjustably mounted on said handle, co-operating means on said slide and said wrench member whereby said slide grips said member at points on opposite sides of one of said jaws for locking said member in any one of its operative positions, and co-operating means on said handle and said slide for frictionally holding said slide in either of its positions. 95

4. In a tool of the class described, a handle, a wrench member pivoted on said handle, said member being provided with a plurality of wrench jaws and with shoulders arranged between said jaws, said member being rotatable to bring the desired jaw into operative position, a slide adjustably mounted on said handle, a pair of lateral extensions on said slide for engaging a corresponding pair of said shoulders, whereby said wrench member is securely locked in operative position, and coöperating means on said handle and said slide for frictionally holding said slide in wrench-locking position, said means permitting adjustment of said slide to unlock said wrench-member. 115

5. In a tool of the class described, a handle, a wrench member pivoted on said handle, said member being provided with a plurality of wrench jaws and rotatable to bring the desired jaw into operative position, a slide adjustably mounted on said 125

- handle, coöperating means on said slide and said wrench member for securely locking the latter in operative position, said means being entirely independent of said jaws, and
- 5 a pair of integral finger pieces projecting laterally from said slide beyond the sides of the handle for manually operating said slide.
6. In a tool of the class described, a handle, a wrench member pivoted on said handle, said member being provided with a plurality of wrench jaws and with shoulders arranged between said jaws, said member being rotatable to bring the desired jaw into operative position, a slide adjustably
- 10 mounted on said handle, a pair of lateral extensions on said slide for engaging a corresponding pair of said shoulders, whereby said wrench member is securely locked in operative position, and a pair of integral
- 15 finger pieces projecting laterally from said slide beyond the sides of the handle for manually operating said slide.
7. In a tool of the class described, a handle, a member pivoted on said handle, said member being provided with a plurality of operative sections and with shoulders between said sections, said member being rotatable to bring the desired section into operative position, a slide adjustably
- 20 mounted on said handle, a pair of lateral extensions at one end of said slide for engaging a corresponding pair of shoulders, whereby said member is securely locked in operative position, an operative head at the
- 25 other end of the slide, said head being in an inoperative position when the slide is in position to lock said member, and a third extension on the first-named end of said slide for engaging one of said shoulders when said slide is in position to project said head into operative position, whereby said member forms a bearing or support for said slide to prevent longitudinal inward movement thereof when said head is in operative
- 30 position.
- 45 8. In a tool of the class described, a pair of spaced supporting plates rigidly connected together near their ends to form a handle, said plates being free to be sprung apart at or near the center, an inwardly extending projection on one of said plates at or near the center thereof, a wrench member pivoted between said plates near one end thereof, said member being provided with a plurality of wrench jaws and rotatable to bring the desired jaw into operative position, a slide adjustably mounted between said plates, and coöperating means on said slide and said wrench member for
- 50 securely locking the latter in operative position, said means being entirely independent of said jaws, said slide having a recess or opening into which said projection enters when the slide is in wrench-locking posi-
- tion, said projection being forced out of said recess or opening when the slide is moved into position to unlock said wrench member.
- 55 9. In a tool of the class described, a pair of spaced supporting plates rigidly connected together near their ends to form a handle, said plates being free to be sprung apart at or near the center, an inwardly extending projection on one of said plates at or near the center thereof, a wrench member pivoted between said plates near one end thereof, said member being provided with a plurality of wrench jaws and rotatable to bring the desired jaw into operative position, a slide adjustably mounted between said plates, and a pair of lateral extensions at one end of said slide for engaging a corresponding pair of shoulders, whereby said wrench member is securely locked in operative position, said slide having a recess or opening into which said projection enters when the slide is moved into position to unlock said wrench member.
- 60 10. In a tool of the class described, a handle, a wrench member pivoted at one end of said handle and provided with a plurality of wrench jaws, said wrench member having a plurality of shoulders between said jaws, a slide adjustably mounted on said handle, a pair of gripping members on said slide for engaging a pair of shoulders to lock said wrench member in the desired operative position, and an extension on said slide arranged to enter one of said jaws when said gripping members are in wrench-locking position, said extension being adapted to engage one of said shoulders when said gripping members are out of locking engagement with said wrench member.
- 65 11. In a tool of the class described, a handle, a member pivoted at one end of said handle, said member being provided with a series of operative openings and with a series of shoulders arranged between said openings, a slide adjustably mounted on said handle, one end of said slide having means to engage a pair of said shoulders and thereby lock said member against rotation, the said end of the slide also having an extension which enters into one of said openings when said member is held locked, said slide being adjustable to unlock said member and move said extension into engagement with one of said shoulders, whereby said member acts as a support or bearing to prevent longitudinal inward movement of said slide, and a head at the other end of said slide, said head being

held in an operative position by said member when said extension engages one of said shoulders.

12. In a tool of the class described, a handle formed of a pair of spaced plates, a member pivotally mounted between said plates near one end thereof and provided with a plurality of operative sections, any one of which may be brought into operative position, said member having shoulders arranged between said sections, a slide adjustably mounted between said handle plates and having three extensions, two of said extensions being arranged to engage a pair of said shoulders for locking said member in the desired operative position, the third extension being arranged to engage one of said shoulders when the other two extensions are out of engagement with said shoulders, and an operative head at the other end of said slide, said head being held by said member in an operative position when said third extension engages one of said shoulders.

13. In a tool of the class described, a handle, a member pivotally mounted at one

end of said handle, said member being provided with a plurality of openings and a plurality of shoulders, a slide adjustably mounted on said handle, an operative head 30 at one end of said slide, and an extension at the other end of said slide adapted to engage one of said shoulders for holding said head in an operative position, said extension being adapted to enter one of 35 said openings when said head is moved into inoperative position.

14. In a tool of the class described, a handle, a wrench member pivoted on said handle and having a plurality of wrench 40 jaws, said member being rotatable to bring the desired jaw into operative position, a slide adjustably mounted on said handle, and a pair of spaced extensions on said slide for gripping said member at two correspondingly spaced points, whereby said wrench member is securely locked in operative position.

In witness whereof, I hereunto subscribe my name this 14th day of August, 1917. 50

ALBERT D. GROVER.
